By S. G. Straus.
ATTORNEY.

UNITED STATES PATENT OFFICE.

JOHN F. BARTLETT, OF DULUTH, MINNESOTA.

THREAD TENSION AND CONTROLLING DEVICE.

1,262,002.

Specification of Letters Patent. Patented Apr. 9, 1918.

Application filed June 18, 1917. Serial No. 175,263.

To all whom it may concern:

Be it known that I, JOHN F. BARTLETT, a citizen of the United States, residing at Duluth, in the county of St. Louis and State 5 of Minnesota, have invented certain new and useful Improvements in Thread Tension and Controlling Devices, of which the following is a specification, reference being had therein to the accompanying drawing.

10 This invention consists of certain improvements in thread tension and controlling devices and relates particularly to such used in the art of manual crocheting or knitting.

One object of the invention is to provide 15 a convenient device of this character to be worn upon the fingers of a person when using thread or yarn as above mentioned, whereby the thread or yarn may be kept at a uniform tension during its use and that 20 without the conscious attention of the wearer.

Another object is to provide a novel form 25 of tension device having means whereby the thread normally tends to remain adjacent the center of the holding means.

Other objects and advantages will appear in the further description of the invention.

In the accompanying drawings forming 30 part of this application and in which like reference characters represent like parts;

Figure 1 is an enlarged side elevation of the device;

Fig. 2 is an edge elevation of Fig. 1, and

Fig. 3 is a transverse vertical sectional 35 view through the center of the adjusting screw.

1 represents the body portion of the device, it being formed preferably of light metal such as aluminum or the like or of 40 other suitable composition and having two circular holes 2 and 3 therethrough, forming a double finger ring designed to be worn upon two adjacent fingers of the hand, as for example, the little finger and the one 45 next to it.

The hand upon which the device is worn is that commonly used in holding the thread or yarn and is ordinarily the left hand. Upon the upper flat surface 4 of the body 50 portion is attached the tensioning device which comprises a thin metal spring yoke 5, upwardly arched, slidably supported upon its extreme ends 6 through which suitable guiding and holding pins 7 pass and are 55 fixed within the body portion 1.

The holes in the ends 6 of the yoke,

through which the pins pass are slightly elongated longitudinally of the yoke to admit of slight movement of the yoke independently of the pins as when the tensioning device is being adjusted.

The central portion 8 of the yoke is of circular form in plan view and dished downwardly about its center forming a concaved portion and through which the shank 9 of 65 the adjusting thumb screw 10 extends. The shank 9 is screw threaded within the body portion 1 and in relation to which it may be adjusted longitudinally by turning.

Between the hub portion of the thumb 70 screw 10 and the yoke 5 is mounted a circular concavo-convex washer 11 substantially identical in shape to the central portion of the yoke 5 and placed with its concaved face 75 toward that of the yoke 5.

The peripheral edges of the washer 11 and the central portion 8 are flared slightly apart forming a somewhat V-shaped groove thereabout for ready and convenient application of the thread or yarn and the contacting 80 portions of the washer and yoke being circular in form and concentric with the shank of the thumb screw and spaced a distance therefrom. Due to this peculiar construction, the thread, when held between the 85 washer and yoke will normally tend to remain against the shank 9, thus provision is made against the thread being easily dislodged from the device.

By being mounted upon two fingers of 90 the hand simultaneously, no trouble whatever is experienced in keeping the device right side up and it is to be understood that various modifications of the specific construction herein shown may be resorted to 95 without departing from the spirit of the invention.

It is obvious that by the longitudinal adjustment of the thumb screw, various sized thread may be held in the device and that 100 any degree of tension desired may be applied thereto.

Having thus described my invention what I claim as new and desire to secure by Letters Patent is:—

1. A thread tensioning and controlling device of the character described, comprising a body portion having two finger holes therethrough and a flat smooth upper surface, an upwardly arched resilient member loosely attached at both ends to the flat surface of the body portion, and having a circular central 105 110

portion, a second circular member coacting with and above the resilient member and between which the thread is held and a thumbscrew extending through the two coacting members and into the body portion.

2. A thread tensioning and holding device of the character described, comprising a body portion having two finger holes therethrough and a straight flat upper surface, an upwardly arched thread engaging member loosely mounted upon the upper surface of the body portion, pins passing through the ends of the arched member and into the body portion, a circular concavo-convex central portion in the arched member, a circular concavo-convex member coöperating with the like central portion of the arched member and intermediate of which the thread is engaged, and a thumbscrew passing through the circular members and into the first mentioned body portion substantially as and for the purpose described.

3. A thread tensioning and holding de-

vice of the character described, comprising a body portion having two finger holes therethrough and a straight flat upper surface, an upwardly arched thread engaging member loosely mounted upon the upper surface of the body portion, means at the ends of the arched member to permit free longitudinal movement thereof, a circular concavo-convex central portion in the arched member, a circular concavo-convex member coöperating with the like central portion of the arched member and intermediate of which the thread is engaged and a thumbscrew passing through the circular member and into the body portion, substantially as and for the purpose described.

In testimony whereof I hereunto affix my signature in the presence of two witnesses.

JOHN F. BARTLETT.
